UNITED STATES PATENT OFFICE.

HARRY R. COREY, OF BROOKLYN, NEW YORK, ASSIGNOR TO AMERICAN CAN COMPANY, OF NEW YORK, N. Y., A CORPORATION OF NEW JERSEY.

TALCUM-POWDER BOX.

Application filed December 17, 1921. Serial No. 523,004.

My invention relates in general to sifter top containers, and more particularly to containers adapted for the packaging of talcum powder and like material.

5 A principal object of the invention is the provision of means for tightly closing such a container in such manner as to prevent, in peculiarly effective manner, the leaking of the contents when the parts are in closed relation.

10 A further object of the invention is the provision of indirect outlet passages for the powder so arranged as to facilitate removal of the powder for use while at the same time providing the effective closing means above referred to.

15 Still another object of the invention is the provision of a talcum powder container of simple and inexpensive construction, possessing the advantages of a non-leaking closure and an efficient outlet for the contents and all the parts being capable of formation through conventional mechanical operations.

20 Numerous other objects and advantages of the invention will be apparent as it is better understood from the following description, which, taken in connection with the accompanying drawings, discloses a preferred embodiment thereof.

25 Referring to the drawings,

Figure 1 is an elevational view of a container in which my invention is embodied;

Fig. 2 is a top plan view of the cap;

30 Fig. 3 is a plan view of the container top with the cap removed;

Fig. 4 is an enlarged section taken vertically through a portion of the top and cap; and

40 Fig. 5 is a vertical section through the top and cap, said parts being shown in separated relation.

45 Upon the drawings which illustrate the invention, the reference numeral 11 indicates the body of a talcum powder box, which in the present instance, is of oval formation and has secured thereto a cover 12 by means of a seam 13 of any preferred form. A sifter top 15 is provided with a central depression 16 in which are perforations 17 spaced as desired. Radial channels 18 are provided in the outer 50 raised portion 19 of the top, these channels, as will be noted by reference to Fig. 3, being each preferably aligned with one of the perforations 17.

55 A cap 21 is adapted to fit over the top 15 and has an inwardly turned flange 22 formed

to frictionally engage the neck 23 of said top in such manner as to permit rotation of the cap. Said cap is provided with a central depressed portion 24 corresponding to the depressed portion 16 of the top and adapted to be seated therein, and has downwardly opening radial channels 25 adapted to form inward continuations of the channels 18 when the cap is in open position, whereby passages are provided between the perforations 17 and 60 perforations 26 in the cap. Cut in the outer part of the cap is a segmental slot 27 which is adapted to engage a stud 28 upon the container top to limit the opening and closing movement of the cap upon said top. It will 65 be observed that rotation of the cap from the open position results in cutting off communication between the channels 18 and 25, and as the elevated portion 19 of the top is in contact with a considerable area of the outer part of 70 the cap and the perforations 17 and 26 are entirely out of registration, accidental leaking 75 is impossible even with finely powdered contents.

It is thought that the invention and many 80 of its attendant advantages will be understood from the foregoing description, and it will be apparent that various changes may be made in the form, construction and arrangement of the parts without departing from the 85 spirit and scope of the invention or sacrificing all of its material advantages, the form hereinbefore described being merely a preferred embodiment thereof.

90 I claim:

1. A sifter top can comprising a body, a top formed with perforations arranged around its center at a distance therefrom, a cap mounted to rotate on said top and formed with sifting perforations which are at a different distance from said center from said 95 perforations of the top, said top having portions for closing the perforations of the cap when the latter is turned to closed position and having channels forming indirect communications between the perforations of the top and the perforations of the cap when the latter is turned to open position.

2. A sifter top can comprising a body, a top and a cap rotary on said top to open or closed 105 position, said top and said cap being each formed with a set of perforations which sets are arranged at different distances from the center of rotation, said top having channels affording communications between the inner 110

and outer perforations, and means for preventing the exit of powder when the cap is turned to closed position.

3. A sifter top can, comprising a body, a top having a central depressed perforate part and being provided with radial channels leading outwardly therefrom, and a cap having a central depressed imperforate part provided with channels extending over the perforate part of said top, said channels being adapted to be turned into and out of registration with said radial channels of the top.

4. A can for talcum powder and the like, comprising a body, a sifter top having a perforate and an imperforate part, and a cap having perforations out of alignment with the perforate part of the top, said top and cap being grooved to provide corresponding channels communicating in open position between the cap and top perforations, and the top being movable to cut off such communication when in closed position.

5. A can for talcum powder and the like, comprising a body, a sifter top having a perforate and an imperforate part, a cap having perforations out of alignment with the perforate part of the top, said top and cap being grooved to provide corresponding channels communicating in open position between the cap and top perforations, and the top being movable to cut off such communication when in closed position, and means comprising a stud on the top and a segmental slot

in the cap for limiting opening and closing movement of the latter.

35

6. A powder can comprising a body having perforations, a cap having perforations and mounted and rotatable on the body so as to surround the perforations of the body, the perforations of the cap being always out of alignment with those of the body, the body and cover having between them channels which lead from the perforations of the body to those of the cap, and the cap having portions which close the perforations of the body when the cap is turned to such closed position.

7. A talcum powder box, comprising a body, a neck part terminating in a top provided with sifter openings, a cap covering said top and also provided with sifter openings which are permanently out of registration with the sifter openings of the top, means in the top and cooperating means in the cap for bringing said two sets of sifter openings into and out of communication.

50

8. A talcum powder box, comprising a body, a top provided with sifter openings, a cap covering said top and also provided with sifter openings which are permanently out of registration with the sifter openings of the top, grooves in the top and cooperating grooves in the cap for bringing said two sets of sifter openings into and out of communication.

55

HARRY R. COREY.
